UNITED STATES PATENT OFFICE.

ROBERT NICOL, JR., OF CHICAGO, ILLINOIS.

DESIGN FOR A CURLING-IRON ORNAMENTATION.

SPECIFICATION forming part of Design No. 21,026, dated September 1, 1891.

Application filed May 18, 1891. Serial No. 393,237. Term of patent 7 years.

To all whom it may concern:

Be it known that I, ROBERT NICOL, Jr., a citizen of the United States, residing at Chicago, county of Cook, and State of Illinois, 5 have invented and produced a new and original Design for the Movable Jaws of Curling-Irons, of which the following is a specification.

The drawing is a perspective representation of a curling-iron having its rear or thumb portion 10 ornamented.

The leading features of my design consist in the ornamentation of the rear portion of the movable jaw of curling-irons, and the design shown in the accompanying drawing is 15 produced by the formation on the upper surface of the rear portion of the movable jaw a depressed two-part panel and in relief on this panel two vine-like sprays. The members of this two-part panel are arranged with the 20 length of the movable jaw, the one nearest its forward end being substantially triangular in form and the panel farthest back, conforming to the outline of that portion of the jaw upon which it is impressed, is surrounded by 25 a marginal raised rib. These two panels are connected by a narrow portion, and the two vine-like sprays arise from the narrow neck and extend in opposite directions across the

face of each panel. The ring farthest back on the iron is indented by two grooves, which, 30 commencing at the upper edge of the bridge on one side, follow each edge of the ring to the opposite side of the bridge. Between these two marginal grooves a third groove commences at the upper edge and on each side of 35 the bridge, but is not continuous around the ring, being replaced on the under side by a series of dots. The bridge between the rings is ornamented with vertical grooves located at intervals in its sides. On each side of the 40 forward ring of this frame, commencing on a line with the lower edge of the connecting-bridge, are five short vertical grooves, the middle one being slightly longer than the others, and from the ends of the outer grooves are 45 two converging grooves, which join in a point directly below the lower end of the longest groove of the five before mentioned.

I claim as my invention—

A design for the surface ornamentation of 50 the movable jaw of curling-irons, herein set forth.

ROBERT NICOL, JR.
